UNITED STATES PATENT OFFICE.

EMMET W. FORAN, OF CUSTER, SOUTH DAKOTA.

SLEEVE-VALVE MOTOR.

Application filed September 10, 1923. Serial No. 661,984.

To all whom it may concern:

Be it known that I, EMMET W. FORAN, a citizen of the United States, residing at Custer, in the county of Custer and State of South Dakota, have invented new and useful Improvements in Sleeve-Valve Motors, of which the following is a specification.

This invention relates to internal combustion engines, particularly those of the so-called valveless type, and has for its object the provision of a novel engine in which use of the ordinary tappet or poppet valve is eliminated, the intake and exhaust being controlled by a rotary valve operating within a sleeve.

An important object is the provision of an engine of this character which is provided with a highly efficient and positive lubricating system which will insure thorough oiling of all the parts at all times so that overheating and burning out of the bearings will be prevented.

Another object is the provision of an engine of this character which will be comparatively simple and inexpensive in manufacture, which will embody the minimum number of parts, which will be positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a side elevation of the engine,
Figure 2 is a plan view thereof.

Figure 3 is a longitudinal section taken axially of all the cylinders,

Figure 4 is a cross section taken through the center of one cylinder,

Figure 5 is a cross section on the line 5—5 of Figure 4,

Figure 6 is a side elevation of the sleeve removed from the engine,

Figure 7 is a side elevation of the valve removed from the engine,

Figure 8 is a plan section of the oil pump,

Figure 9 is a section on the line 9—9 of Figure 8.

Referring more particularly to the drawings the numeral 10 designates the cylinder block mounted upon a crank case 11 and carrying a removable head 12. The block may be formed with any desired number of

cylinders though in the present instance four are shown as being sufficient to illustrate the construction, operation and advantages. Journaled through the crank case and mounted in any suitable or ordinary bearings is the crank shaft 13 formed with a plurality of crank portions 14 and carrying the usual fly wheel 15. The forward end of the crank shaft may be constructed for engagement by a suitable crank to effect turning over of the motor for starting though these details are old and well known and no claim is made thereto. Operating within the cylinders are pistons 16 connected with connecting rods 17 which are in turn engaged upon the crank portions 14 of the crank shaft in the usual manner.

The head 12 is formed with a chamber 18 within which is located a removably mounted sleeve 19 which is held stationary by any desired means. The head is formed with ports 20 for the intake and exhaust of fuel mixture and burnt gases respectively. The top of the head is formed with two exhaust ports 21 which lead into an exhaust manifold 22 while the central portion of the head is formed with a single port 23 leading to the intake manifold 24 which must naturally lead from any suitable carburetor not shown. The sleeve 19 is formed with ports 25, 26 and 27 which register with the ports 20, 21 and 23 respectively.

Journaled through the sleeve 19 is a rotary valve 28 equipped at one end with a sprocket 29 about which is trained a silent chain 30 which is in turn trained about a sprocket 31 on the crank shaft so that the valve will be positively driven thereby. This valve 28 is provided with eight ports 32 arranged at various angles and is also formed with three deep slots 33 and 34. The former of these slots are arranged near the ends and the latter is at the center. The ports 32 are designed to register with the ports 25 while the slots 33 register with the ports 26 and the single slot 34 registers with the port 27. The valve is also provided with a plurality of spring rings 35 located between the ports as shown for the purpose of preventing loss of compression and which rings are comparatively wide and fastened in their grooves so that they must turn with the valve. The ports 32 in the valve are connected by channels 36 and 37, the former of which leading to the slots 33 and the latter of which leads

2
to the slot 34 so as to control the inlet and exhaust.

For effecting lubrication I provide a suitable oil pump 38 driven by or from the crank shaft by the means indicated at 45 and having connected therewith distributing pipes 50 which are brought to certain points to be lubricated as shown. The cylinders and most other parts are lubricated by the splash as it is not necessary to provide a force feed in every instant. The valve is formed with oil grooves 51 which will provide adequate means for effecting lubrication. The engine is of course provided with the usual water jacket 52 and spark plugs 53 located at the points shown or at some other location.

In the operation it will be apparent that when the motor is running, the crank shaft drives the valve and as the various ports in the valve register with the ports in the sleeve which in turn register with the ports in the head, the exhaust of burnt gases and intake of fresh fuel mixture is controlled. As the various passages in the rotary valve communicate always with the slots in the valve and as these slots in turn always communicate with the intake and exhaust ports in the sleeve it is obvious that the intake and exhaust occur at the very instant that the ports 25 are uncovered so that there will be no retardation of the action which might cause sluggishness on account of back pressure or any other cause.

From the foregoing description and a study of the drawings it will be apparent that I have thus provided a simply constructed and consequently inexpensive engine which entirely eliminates use of the ordinary tappet valves and which would therefore be far more silent in operation than most motors in addition to furnishing maxi-

mum power and being free from carbon trouble.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

In a multiple cylinder internal combustion engine, a head common to and closing the ends of all the cylinders, said head having a cylindrical bore therein, a sleeve stationarily mounted within said bore, the head having chambers communicating with the bore, and with the respective cylinders, said sleeve having a pair of ports at each chamber communicating therewith, and a solid cylindrical valve rotatably mounted within the sleeve and constrained from longitudinal movement, said valve having a central groove in its periphery and passages communicating at their inner ends with said groove, the valve having ports at its outer ends of said passages and at points intermediate the ends of the passages for communication with certain of said first named ports, the end portions of the valves being provided with peripheral grooves registering constantly with exhaust passages formed in the head, said first named peripheral groove registering constantly with an intake passage formed through the head and the valve being provided with longitudinally extending passages communicating at their outer ends with said exhaust ports and communicating at their inner and intermediate points with the remaining ones of said first named ports.

EMMET W. FORAN.
